CLAIM

The ornamental design for a therapeutic self massage roller, as shown and described.

DESCRIPTION

FIG. 1 is a perspective front view of a therapeutic self massage roller showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the figures are for the purpose of illustrating portions of the therapeutic self massage roller, which form no part of the claimed design.
